18 Claims. (Cl. 66—54)

The invention relates to an improvement of the apparatus for making heel or toe pouches in seamless women's stockings and the like, as are produced by continuous methods on circular knitting machines.

In the method of U.S. application Serial No. 166,615, filed January 16, 1962, and assigned to the assignee of the instant application, a pouch is knitted in the tube by the gradual enlargement of the stitch length along a portion of the periphery of the needle cylinder and the transition from one loop length to the other in the fashioned heel or toe pouch can take place continuously both in the longitudinal and in the circumferential direction. A three dimensional control cam rotates synchronously with the needle cylinder and serves for the performance of the process by controlling the depth to which one or more needle cams draw the needles. However, the manufacture of the three dimensional cam surfaces is relatively difficult and expensive. Furthermore, a second control cam would be necessary for the formation of a corresponding toe pouch.

In the present invention, the three dimensional cam is replaced by a cam which rotates synchronously with the needle cylinder, and means are provided for varying the cam working height during its rotation according to a program. This cam can be formed by a sliding skew cylinder and a cam ring that can be displaced with respect to a fixed ring by means of the said sliding skew cylinder. The cam ring can be displaced in relation to the fixed ring by means of a spindle or other prior-art displacing devices rather than by the sliding skew cylinder. Cam working height is determined by the extent to which the cam ring extends beyond the fixed ring. The portion of the control ring which extends out beyond the periphery of the fixed ring operates as a cam, and it can be arcuate or it can have any other desired cam shape. In order to be able to fashion a toe pouch on the opposite side of the needle cylinder, the cam ring is provided so that it can be displaced in two opposite directions in relation to the fixed ring.

The invention will be described further with reference to the drawings, wherein an embodiment thereof is depicted.

FIGS. 1 and 2 show the apparatus of the invention in section with two different cam settings;

FIGS. 3a, 3b, and 3c show schematically in section three extreme settings of the apparatus of the invention;

FIG. 3d shows developments of curved ends of sleeves according to the invention;

FIG. 4 shows in plan view cam ring positions corresponding to the positions of FIG. 3;

FIG. 5 shows a stocking element manufactured with the apparatus of the invention;

FIG. 6 shows a stocking made in accordance with the invention;

FIG. 7 is an isometric view of a cylinder outfitted with a movable stitch cam;

FIG. 8 is a plan view of some of the parts shown in FIG. 1; and

FIG. 9 is an isometric view of a part of the mechanism shown in FIG. 8.

2

In the various views of the drawings, like reference characters refer to corresponding parts.

The invention provides a circular knitting machine for the knitting of tubular goods (see FIG. 7) and the machine is adapted to selectively work pouches into the goods by a variation of the longitudinal length of the knit loops. The knitting machine comprises a cylinder having needles disposed axially about the periphery thereof and mounted thereon for axial movement thereof with respect to the cylinder for the knitting operation. The cylinder rotates continuously in one direction, and the needles are provided with needle butts for cooperation with stitch cams for actuation of the needles. The cylinder rotates relative to the stitch cams, and, accordingly, cooperation of the stitch cams and the needle butts occurs so as to provide the knitting action of the needles. The machine includes a pouch working cam and means for rotating the pouch working cam in synchronism with the movement of the needle cylinder. Cam followers are provided for cooperation with the pouch working cam, and, further, means are provided which interconnect the cam followers and the stitch cams and are effective to move the stitch cams axially relative to the needle cylinder in response to action of the pouch working cam on the cam followers. Thereby, the axial stitching movement of the needles and therefore longitudinal length of the knit loops can be varied. The pouch working cam is distinct from the three dimensional pouch working cam of the aforementioned application Serial No. 166,615, in that insofar as its operation as a cam is concerned, it is a two dimensional cam. Moreover, the pouch working cam according to the invention is provided so that its working height can be varied, whereby the magnitude of the cam action on the cam followers can be varied and in turn axial stitching movement of the needles can be varied. The machine also includes programming means for coordinating operation of the means controlling the working height of the pouch working cam, and the rotation of the needle cylinder, whereby to provide longitudinally elongated stitches over an area of the knit goods so that the pouch is formed therein.

The pouch working cam can be in the form of a plate. A support for the plate is fixedly secured to a shaft which is arranged to rotate in synchronism with the needle cylinder. The plate is slidably mounted on the support for movement thereof so that it can project radially outwardly thereof to provide as the pouch working cam working height, that portion of the plate projecting outwardly of the support. The plate forming the pouch working cam can be movable along a radius between a position of zero working height and a position of finite working height. With the pouch working cam in a position of zero working height, the cam follower can ride on the support for the pouch working cam, while with the pouch working cam in a position of finite working height, the cam follower rides on the working surface of the cam which projects beyond the support.

A feature of the machine of the invention is that means for knitting pouches at circumferentially spaced intervals can be conveniently provided. Thus, in embodiments wherein the pouch working cam is movable between a position of zero working height and one position of finite working height, the machine is outfitted to knit pouches at one circumferential location. The pouch working cam, however, can be provided so that it is movable between a position of zero working height along either of two radii to, respectively, a first position of finite working height and a second position of finite working height. In those embodiments wherein the cam is movable along two radii between a position of zero working height and two positions of finite working height, pouches can be worked

at circumferentially spaced locations. Such pouches can as well be axially spaced along the net goods. Thus, the machine is well-suited for the knitting of heel and toe pouches.

The means for controlling the sliding movement of the pouch working cam can comprise a first sleeve axially slidably mounted on a stub shaft which is free to rotate in the first sleeve, and a second sleeve fixedly secured to the stub shaft. Adjacent ends of the said first and second sleeves are in abutting relation, and the adjacent ends are contoured for cooperation so that the rotation of the second sleeve with the stub shaft holds the first sleeve axially of the shaft. The programming means is operatively connected to the stub shaft and controls the rotation thereof, whereby the axial position of the said first sleeve is controlled by the programming means. To coordinate the operation of the programming means with the pouch working cam, means interconnect the first sleeve and the plate forming the pouch working cam so that the position of the cam is controlled by the axial position of the said first sleeve on the stub shaft.

For interconnection of the programming means and the pouch working cam, an obliquely mounted cylinder can be used. Thus, a cylinder can be obliquely mounted on the shaft carrying the support for the pouch working cam. The obliquely mounted cylinder is mounted on such shaft for rotation therewith and so that it is axially movable therealong. Further, the obliquely mounted cylinder extends through the plate which forms the pouch working cam, and the said cylinder is in sliding contact with the cam plate so that axial movement of the cylinder along the shaft will impart to the cam plate a movement radially of the shaft, whereby to provide variation in the working height of the cam. A connector is provided which connects the oblique cylinder with the said first sleeve on the stub shaft. Thus, the action of the programming means which controls the position of the said first sleeve on the stub shaft, is effective, by reason of the said connector, to control the axial position of the oblique cylinder on its shaft, and, hence, to control the position of the pouch working cam and, therefore, the working height of the pouch working cam.

Referring to the drawings, as can be seen in FIG. 7, a circular knitting machine according to the invention includes a needle cylinder Z having knitting needles N mounted thereon for axial movement along the periphery thereof. The knitting machine of the invention rotates continuously in one direction. During rotation of the knitting needle cylinder, the needle butts B enter the stitch cam IV. The stitch cam IV is contoured to engage the needle butts and move the same up and down to provide the knitting action of the needles. In the device of the invention, provision is made for moving the stitch cam IV axially relative to the cylinder after the needle butts have entered the stitch cam, whereby the extent of movement of the needles relative to the needle cylinder is varied. Thus, by controlling the axial position of the stitch cam, the movement or flow of the needle can be controlled so that the longitudinal length of the knit loop can be controlled.

As is shown in FIG. 7, the stitch cam IV is mounted on cam carrier 92, which, in turn, is mounted for movement axially with respect to the needle cylinder in a cam ring 9. The cam carrier 92 has an outwardly projecting arm 83, and spring F is connected to the arm 83 and urges it upwardly into a neutral position, i.e. a position for the knitting of loops of normal loop length. For movement of the cam carrier 92, there is provided the pivot arm 82 which is pivoted to the support arm 93. One end of the pivot arm 82 works on the arm 83 of the cam carrier, while the other end of the arm 82 is connected to a link 81. By suitable actuation of the link 81, the desired movement is imparted to the cam carrier. The invention is particularly concerned with

the manner in which such movement is imparted to the linkage 81.

As indicated in FIG. 1, the apparatus of the invention for moving the stitch cam is mounted directly on the machine frame 7, bracket 71 being able to be made in one piece with the frame. Shaft 11 simultaneously serves as the drive shaft of the machine, being connected by a coupling 74 to the driving motor 73 which is flange-mounted on the machine frame. The needle frame assembly can be mounted atop the flange 72. On shaft 11 there is mounted the gear (not shown) for driving the needle cylinder, and the dial disc (not shown) can be connected to the shaft 11. The apparatus of the invention can thus be installed in a simple manner on any desired type of circular knitting machine with any desired number of feeds and stitch cams. It is only necessary to see to it that the stitch cam on each feed is vertically displaceable on the cam ring, as shown and described with reference to FIG. 7.

Upon the shaft 11, which revolves at the same rotatory speed as the needle cylinder, there is fastened by means of a boss 310 a support or fixed ring 1. Further, a sliding cylinder 100 is mounted displaceably on shaft 11, the latter passing through the sliding cylinder obliquely and the obliquely mounted cylinder is keyed to the shaft by means of a spline 12. On sliding cylinder 100 there is mounted a pouch working cam 2 whose boss 2' slides on the oblique or skew cylinder 100, while it is mounted on the support ring 1 by means of screws 111 in such a manner that it is displaceable in relation to said fixed ring 1 along the guide slots 112. The pouch working cam 2 and the oblique cylinder 100 and the fixed ring 1 thus rotate together with shaft 11.

A connector or shift claw 101, for the purpose of shifting skew cylinder 100 on shaft 11, engages in an annular groove 110 in skew cylinder 100. Shift claw 101 is displaceably mounted by means of a sleeve 105 on the stub shaft 103 which is mounted in a bracket 71 affixed to the machine frame 7, and is urged by a spring 104 against a sleeve 102 rigidly affixed to the stub shaft. The mutually contacting ends of the two sleeves 102 and 105 are shaped like cams; for example, they are contoured as interfitting helices or as a cam and follower. By rotating shaft 103, these cam members are rotated against one another, the sleeve 102 rotates with the shaft 103 and the sleeve 105 remains fixed relative to the shaft 103, and sleeve 105 is thereby displaced against the pressure of spring 104. Stub shaft 103 is made to rotate by a ratchet wheel mechanism as is shortly to be described and as is disclosed in patent application Serial No. 166,615.

Disposed at intervals about the support 1 and the pouch working cam 2 are the cam followers R-I, R-II, R-III and R-IV (see FIG. 8), in the same angular relationship as the corresponding stitch cams about the needle cylinder, and they are connected one to each stitch cam by appropriate means such as bell cranks 8 and linkage 81. The followers R extend over the support 1 and the pouch working cam 2.

The manner in which the movement of the stub shaft 103 is controlled will be described with reference to FIG. 8 and FIG. 9. A ratchet wheel device including the ratchet wheels 41 and 42 are mounted on stub shaft 103 so that the shaft will be rotated upon rotation of the ratchet wheels. The ratchet wheels are connected together by a pin 43 so that any movement of the one will be directly imparted to the other. The ratchet wheel 42 has a full complement of teeth while the ratchet wheel 41 is lacking a full complement as can be seen by the gap 41' in FIG. 9. A pair of pawls 45 and 46 pivoted about the pin 44 are provided for engaging in rotating the ratchet wheels 41 and 42, respectively. The pin 44 is carried by a pawl lever 4 which is subjected to an oscillating movement by the connecting rod 3 which is pivotably connected to the pawl lever 4 and is eccentrically mounted on the shaft 11.

The mounting of the connecting rod 3 on the shaft 11 is such that rotation of the shaft 11 will cause the connecting rod 3 to oscillate. This mounting is effected by providing the eccentric disc 31 secured to the shaft 11 for rotation therewith, while at the same time the eccentric disc 31 is in sliding engagement with the eccentric opening 31a in the end of the connecting rod adjacent the shaft 11. Thus, rotation of the shaft 11 imparts a cranking motion which causes the connecting rod 3 to oscillate. Oscillation of the pawl lever 4 will cause the pawls 45 and 46 to engage the ratchet wheels 41 and 42 and thereby cause their rotation. Means are provided, however, to selectively prevent rotation of the ratchet wheels 41 and 42 even though the pawl lever 4 oscillates. This means consists of a shield 47a carried on the end of a lever 47 which is movable to a position between the tip of the pawl 46 and the ratchet wheel 42 to prevent the pawl 46 from engaging ratchet wheel 42. The lever 47 is rotatably mounted on stub shaft 103 and is actuated by rods 48 and 49. These rods 48 and 49 are in turn actuated to permit the knitting of heel or toe pouches by a chain cam 5 running on sprocket wheel 5a. The chain and sprocket wheel together with the chain cam 5 function as a programming device.

During normal operation of the knitting machine when pouches are not being knit, whereas the connecting rod 3 is oscillated so that the pawls 45 and 46 in turn are oscillated, yet the pawls do not actuate the ratchet wheels 42 and 41 since pawl 46 is maintained out of working engagement with its ratchet wheel 42 by the shield 47a, and, pawl 45 is ineffective to actuate its ratchet wheel 41 because the pawl 45 is, during the said normal operation, in engagement with the pawl gap 41' and this gap is elongated so that the throw of the pawl 45 does not traverse the full length of the gap 41' as is essential to actuation of the wheel 41 by its pawl 45.

When a pouch is to be knit, the programming means comprising the sprocket wheel and chain 5a, bring the sprocket wheel cam 5 into engagement with the arm 49. This engagement results in actuation of the arm 48 which in turn actuates the pivot arm 47 so that the shield 47a is retracted and the pawl 46 is permitted to engage its ratchet wheel 42. This engagement of the ratchet wheel 42 moves the ratchet wheel 41, since both ratchet wheels rotate together on the shaft 6, and upon such movement of ratchet wheel 41 the gap 41' is moved past the pawl 45 so that the pawl 45 and its ratchet wheel 41 are placed into engagement. The oscillation of the connecting rod 3 will thereafter be effective to rotate the ratchet wheels by operation of the pawl 45, until the pawl 45 comes to an elongated pawl gap such as the gap 41'. The shield 47a for ratchet wheel 42 is permitted to move to the position shown in FIG. 9 immediately after the pawl 45 has been brought into working engagement with its ratchet wheel 41.

The manner of operation of the apparatus is as follows: During the knitting of the leg, loops of the same size are knitted over the entire periphery of the cylinder, and the cam followers R are not moved by the pouch working cam 2. The cam followers R therefore run only on the support 1, and the pouch working cam 2 is placed in such a position that it does not project beyond the periphery of the support 1 and consequently does not engage the followers R. This basic position corresponds to the setting shown in FIG. 1 and also in FIG. 3a, of the oblique cylinder 100, and to the setting of the two sleeves 102 and 105 shown in FIG. 1.

As soon as the heel pouch has to be knitted on the stocking, the ratchet wheel mechanism that drives stub shaft 103 is activated by a lift on the chain cam. See the foregoing description of FIGS. 8 and 9.

In other words, upon each rotation of shaft 11 or of the needle cylinder, the stub shaft 103 is turned by an amount predetermined by the ratchet wheel mechanism, until the stub shaft 103 has completed one full revolution. The rotary movement of shaft 103 causes the sleeve

102 rigidly affixed to shaft 103 to turn, and sleeve 105 of the shift claw 101 is thereby displaced against the bias of spring 104. The oblique cylinder 100 disposed on the shaft is thereby shifted in the direction of the arrow 101a.

5 This produces a displacement of the pouch working cam 2 on its support 1. (See FIG. 2.) The portion of pouch working cam 2 which, as a result of the shift, projects beyond the periphery of the fixed ring 1, is the working height of the pouch working cam and lifts the cam followers R upon each revolution so that upon each rotation of the needle cylinder, the stitch cams are actuated accordingly.

15 The continuous displacement of the stitch cams causes the needles to draw the yarn lower, and the looping action is influenced in such a manner that a heel pouch is formed on the stocking. When stub shaft 103 has performed one rotation, the pouch working cam 2 is again in the basic position shown in FIG. 1 and all feeds form loops of the same size over the entire periphery of the cylinder.

20 FIG. 3d shows a development curve x corresponding to sleeves 102 and 105. A displacement of oblique cylinder 100 and hence of the pouch working cam takes place only toward one side and along one radius. This displacement is from the basic position M to the extreme heel setting F' and back again. This movement of the pouch working cam corresponds to movement from a position wherein the working height of the cam is zero to a position wherein the cam projects beyond its support 1 and is at a maximum height, and back again to the zero position.

25 The ratchet wheel mechanism can also be so arranged that the further advancement of control shaft 103 is interrupted in the extreme heel position F' for a number of courses, and the pouch working cam 2 does not return to its basic position M until after those courses. In this case, one of the ratchet wheels 41 must have an additional gap in its periphery, by which the stoppage of the ratchet wheel mechanism is brought about, the action of the latter mechanism being restored by another lift on the chain cam.

30 According to an alternative of the subject of the invention, a pouch can be formed alternately on both sides of the stocking, using the same apparatus. The heel and the toe pouches can be formed. FIG. 5 shows the foot of a stocking in which a heel pouch F was first knitted and then, after a predetermined plain instep length, a toe pouch S was knitted on the other side of the tube. Due to the toe pouch S, the finished stocking (FIG. 6) has a substantially better fit in the toe as well. In FIG. 3d, the curve y is a development of sleeves such as 102 and 105 but contoured for the production of a heel and toe pocket. The oblique cylinder 100 mounted on shaft 11 in this case can be shifted in both directions through the zero or basic position M. In this embodiment, the pouch working cam is provided so that it is movable between a position of zero working height and two positions of finite working height.

35 In FIG. 4, pouch working cam 2 is shown in extreme position 2 (F') for the fashioning of the heel pouch, and, as indicated by the dash-dotted line, in position 2 (S') for the fashioning of the toe. The cam followers R-I, R-II, R-III and R-IV are thus lifted on the opposite portion of support 1 according to whether the heel or toe pouch is being knit. In the knitting of the toe pouch, the stitch cams are actuated whenever the sector of the needle cylinder opposite the heel half turns past them. In the basic position or zero position the stationary support 1 and pouch working cam 2 coincide with one another and there is no actuation of the stitch cams (see FIG. 3b).

40 FIGS. 3a, 3b and 3c and FIG. 3d show the corresponding positions of the oblique cylinder 100, which is first lifted according to curve y from position M to position F' and then back again, while stub shaft 103 performs half a revolution. When the heel pouch is completed, the control ring 2 again finds itself in the basic or zero

position M and remains there until the toe pouch is to be made. Then the skew cylinder 100 is gradually brought into the position indicated by S' on curve y while the toe pouch is formed. Pouch working cam 2 is thus shifted to the opposite side of the support 1, so that the followers R then run on the cam 2 as indicated by the dash-dotted lines and over the circular ring 1 indicated by the solid line (FIG. 4). When the toe pouch is completed, the control cylinder 100 is back in its zero or basic position M. During this time, stub shaft has again performed half of a revolution.

According to whether only a heel pouch or a heel pouch and a toe pouch are to be knitted, sleeves 102 and 105 must have a curvature corresponding to x or y as shown in FIG. 3d. The shape of curves x or y can be of various forms according to what form the heel or toe pocket is to possess.

This improvement of the apparatus of patent application Serial No. 166,615 not only has the advantage of simpler construction, but also it makes possible the production of heel and toe pouches one after the other with the same apparatus. The shape of the pouch can also be determined by the shape of the portion of the pouch working cam that projects beyond the circular fixed ring 1. The said portion can be arcuate or ellipsoidal, or it may have the shape of any other desired curve. The simplest form of the pouch working cam is that of a circle of the same diameter as the support 1. Heel and toe pouches are thus formed which are equal in breadth and depth. By the use of different shapes in each half of the control disk, a different shaping can be achieved between the heel and the toe pouch. By changing the number of teeth in the ratchet wheel and by varying the number of gaps in the teeth for the purpose of interrupting the advancement, the length of the pouch can be varied, while a change in the sleeve curves x and y will produce a change in the depth of the pouch.

While the invention has been described with reference to particular embodiments thereof, various modifications and alterations will occur to those skilled in the art, and it is intended to secure by the following claims all such alterations.

What is claimed is:

1. A circular knitting machine for the knitting of tubular goods and adapted to selectively work pouches into the goods by variation of the longitudinal length of the knit loops while the machine is in continuous rotary motion, said knitting machine comprising:

- (a) a cylinder having needles disposed axially about the cylinder and mounted thereon for axial movement thereof with respect to the cylinder for knitting operation, said needles having needle butts for actuation of the needles;
- (b) a stitch cam for cooperation with the needle butts to actuate said needles for the knitting operation;
- (c) means for rotating said cylinder relative to said stitch cam for cooperation of the stitch cam with the needle butts to provide the knitting operation of the needles;
- (d) a pouch working cam and means for rotating the pouch working cam in synchronism with the said movement of the needle cylinder;
- (e) a cam follower for cooperation with the pouch working cam;
- (f) means interconnecting said cam follower and stitch cam and effective to move the stitch cam axially related to the needle cylinder in response to action of the pouch working cam on the cam follower, whereby to vary the axial stitching movement of needles, and therefore the longitudinal length of the knit loops;
- (g) control means for the pouch working cam for changing the working height of said cam whereby the magnitude of the cam action on said cam fol-

5
10
15

lower can be changed and in turn axial stitching movement of the needles can be changed; and

(h) programming means for coordinating operation of the said control means with rotation of the needle cylinder to provide longitudinally elongated stitches over an area of the knit goods to provide a pouch therein.

2. A circular knitting machine according to claim 1, the said pouch working cam (d) being a plate, a support for said plate fixedly secured to a shaft rotatable to provide said synchronism of the pouch working cam and the needle cylinder, said plate being slidable mounted on said support for movement so that it can project radially outwardly thereof to provide as the pouch working cam working height, that portion of the plate projecting outwardly of the support as aforesaid.

3. A circular knitting machine according to claim 2, said control means (g) for the pouch working cam being a cylinder obliquely mounted on said shaft for rotation therewith, said obliquely mounted cylinder extending through the said pouch working cam plate and slidably contacting said plate, said obliquely mounted cylinder being axially movable along said shaft, said axial movement of the oblique cylinder imparting movement of the cam plate on its support as aforesaid, and means for controlling the axial position on said shaft of said obliquely mounted cylinder.

4. A circular knitting machine according to claim 2, said control means for the pouch working cam controlling said sliding movement of said plate on said support, and comprising a first sleeve axially slidably mounted on a stub shaft which is free to rotate in said first sleeve, a second sleeve fixedly secured to said stub shaft, adjacent ends of said sleeves being in abutting relation and being contoured for cooperation so that the rotation of the second sleeve with the stub shaft moves the first sleeve axially of the shaft, and means interconnecting the said first sleeve and said plate forming the pouch working cam for control of the position of the cam according to the axial position of the first sleeve on the stub shaft, said programming means (h) including said stub shaft.

5. A circular knitting machine according to claim 4, and a cylinder obliquely mounted on said shaft for rotation therewith and axially movable along said shaft, said obliquely mounted cylinder extending through and being in sliding contact with the plate forming the pouch working cam, whereby axial movement of the oblique cylinder on said shaft is effective to control movement of the cam plate on its support as aforesaid, said means interconnecting the said first sleeve and said oblique cylinder, whereby the oblique cylinder is moved along its shaft according to the movement of said second sleeve on its stub shaft.

6. A circular knitting machine according to claim 5, the working surface of the pouch working cam being arcuate.

7. A circular knitting machine according to claim 1, said pouch working cam (d) being a plate, said plate being movable in the plane thereof radially of its axis of rotation, said control means (g) for the pouch working cam being effective to control the position of the cam in said plane; whereby to control the working height of said cam.

8. A circular knitting machine according to claim 7, the working surface of the pouch working cam being arcuate.

9. A circular knitting machine according to claim 7, the said plate forming the pouch working cam being movable along a radius between a position of zero working height and a position of finite working height.

10. A circular knitting machine according to claim 9, the plate forming the pouch working cam being movable along two radii between a position of zero working height and two positions of finite working height.

11. A circular knitting machine according to claim 2, the said plate forming the pouch working cam being

movable along a radius between a position of zero working height and a position of finite working height, the finite working height of the cam being the height to which it extends outwardly of said support.

12. A circular knitting machine according to claim 11, said cam follower (e) riding on the said support and the pouch working cam, respectively, according to the position of the cam on said support of zero working height and finite working height.

13. A circular knitting machine according to claim 11, the plate forming the pouch working cam being movable along two radii between a position of zero working height and two positions of finite working height.

14. A circular knitting machine according to claim 13, said cam follower (e) riding on the support for the pouch working cam and the pouch working cam, respectively, according to the position of the pouch working cam having finite working height and zero working height.

15. A circular knitting machine according to claim 5, the said plate forming the pouch working cam being movable along a radius between a position of zero working height and a position of finite working height, the finite working height of the cam being the extent to which

it projects radially outwardly of its support as aforesaid.

16. A circular knitting machine according to claim 15, wherein the cam follower (e) rides on the support for the pouch working cam and the pouch working cam, respectively, according to the position of the cam of zero working height and finite working height.

17. A circular knitting machine according to claim 15, the plate forming the pouch working cam being movable along two radii between a position of zero working height and two positions of finite working height, the pouch working cam projecting radially outwardly of its support as aforesaid when in a position of finite working height.

18. A circular knitting machine according to claim 17, wherein the cam follower (e) rides on the support for the pouch working cam and the pouch working cam, respectively, according to the position of the cam of zero working height and finite working height.
